TUNED OSCILLATOR CIRCUIT

Browder J. Thompson, Summit, N. J., assignor
to Radio Corporation of America, a corpora-
tion of Delaware

Application September 29, 1934, Serial No. 746,124

12 Claims. (Cl. 250—40)

This invention relates to a new form of short wave tuned oscillatory circuit which is characterized by extremely low loss.

The customary tuned circuits used on wave lengths of several meters and less comprise parallel or concentric lines having distributed constants, and small circuits having lumped inductance and capacitance. Of these, only the concentric lines give high impedance, since the radiation, 10 eddy current, and stray dielectric losses of the other circuits are usually high. Concentric lines have the disadvantage of requiring a conductor at least one-quarter of a wave length long.

It has been proposed to provide a tuned circuit 15 consisting of two copper hemispheres supported on a copper rod with flanges on the hemispheres forming a tuning capacity, while the supporting rod forms the inductance. Such an arrangement, however, introduces considerable loss in the circuit, because of the high external electrostatic field set up. For the same reason, the tuning is affected by stray capacitances.

The present invention provides a highly efficient tuned oscillatory circuit having substantially 20 no external magnetic or electric field, and this is achieved by the use of inner and outer conductors, the surface of the outer conductor being substantially continuous electrically so that there is no external magnetic or electric field, and the inner 25 conductor being connected to the external elements of the circuit by means of one or more leads extending through the outer conductor. Although it is appreciated that there are some losses produced by the connecting leads, the losses consist principally of resistance losses of the inner 30 conductors and can be made to be very low. One advantage of the present invention lies in the substantial freedom of the circuit from the effects of 35 stray tuning due to movements of dielectrics and conductors near the surface.

The invention is described in more detail in connection with the accompanying drawing, wherein Figs. 1-3 illustrate different preferred embodiments of the invention.

Fig. 1 shows a cross section of a tuning circuit 40 comprising a continuous hollow sphere 1, preferably copper, enclosing two rods 2, 3 with the inner ends terminating in discs 4, 5 in the center to form a tuning capacity, the length of rod between 45 discs 4, 5 and the surface of sphere 1 serving as the tuning inductance. Leads 6 are brought out of the tuning circuit through holes in the sphere. These leads can be tapped off anywhere along the rods to match any external impedance.

Fig. 2 shows another embodiment which com-

prises a metallic cylinder 7, preferably copper or brass, enclosing copper rods 8, 9 terminating in discs 4, 5 to form the inductance and capacitance respectively, as in Fig. 1. Rod 8 is herein shown threaded at the end to permit variation in the 5 capacity between the discs 4, 5, merely by a turn of the tuning knob 10. This arrangement is simpler to construct than the spherical arrangement of Fig. 1, and possesses all of the advantages 10 of the latter.

In Fig. 3 is shown an arrangement which, in effect, is one-half of that of Fig. 2, with the lead 11 brought out from the end of the support rod 12. The plate 13 at the free end of the rod 12 provides one terminal of a capacitance whose 15 other terminal is the outer surface of the cylinder. The value of this capacitance may be adjusted by varying the length of rod 12. This embodiment has a considerable advantage in mounting, as the 20 circuit can be placed directly on the ground plate of the apparatus.

Water cooling of the inner conductor 12 may be provided, if desired, by making the conductor hollow and causing a flow of cooling fluid through it by means of an internal tube. Since, at high frequencies, the skin effect causes practically all the current to flow near the surface of the conductor, it will be readily understood that the resistance 25 would not be appreciably increased by removing material from the interior of the conductor. For 30 the same reason, very little loss is introduced by the cooling fluid. If mercury is employed for the cooling, little or no loss will be introduced due to it comparatively low resistance.

Another advantage of the present invention, 35 besides that of very low loss, is that the improved oscillatory circuits enable tuned circuits to be constructed for very short wave lengths of the order of one meter and less, while still providing 40 appreciable lumped capacity, since the inductance can be made very low.

Although the arrangements illustrated in the drawing are preferred and have been shown to be symmetrical, it should be understood that the 45 enclosing surface need not have any symmetrical shape or be a surface of revolution in order to practice the invention; nor is it necessary that the inner conductors be axially located or the condenser be substantially in the center. Lack 50 of symmetry of, or small openings in, the outer surface have no serious adverse effect, and, electrically, are not greatly inferior to any of the idealized structures illustrated. The essential 55 thing is that the outer surface be substantially

continuous electrically, so that there is no external magnetic or electric field.

What is claimed is:

1. An ultra high frequency tuned oscillatory circuit comprising a container in the form of a metallic surface of revolution, a lumped capacitor substantially in the center of said surface of revolution, and connected to said surface by inductance in the form of support rods, and a lead 5 within said surface of revolution connected to the outer surface of each of said support rods between the ends thereof and extending therefrom externally of and through said surface of revolution, said leads being physically separated from each other.
2. An ultra high frequency oscillatory circuit comprising a substantially enclosed metallic surface of revolution, a capacitor comprising two separated plates substantially in the center of 10 said enclosed surface of revolution, a metallic supporting rod devoid of concentrated reactance directly connecting each of said plates to said surface, said rods forming an inductance which, taken together with the plates of said capacitor, 15 comprise the oscillator circuit, the adjacent ends of said rods being separated substantially by the distance between said plates, and leads coupled to the outer surface of said rods and extending substantially perpendicular thereto and through 20 said surface of revolution.
3. A high frequency tuned oscillatory circuit in accordance with claim 2, characterized in this that said enclosed surface of revolution is a sphere.
4. An ultra high frequency oscillatory circuit comprising a substantially enclosed cylinder, a capacitor comprising two separated plates substantially in the center of said enclosed cylinder, a metallic supporting rod devoid of concentrated 25 reactance directly connecting each of said plates to a wall of said enclosure, said rods forming an inductance which, taken together with the plates of said capacitor, comprise the oscillatory circuit, the adjacent ends of said rods being separated 30 substantially by the distance between said plates, and leads coupled to said rods and extending substantially perpendicular thereto and through 35 said cylinder.
5. An ultra high frequency oscillatory circuit comprising a substantially enclosed metallic surface of revolution, a capacitor comprising two plates substantially in the center of said enclosed surface of revolution, a metallic supporting rod for each plate of said capacitor connecting the 40 plate to the surface, said rods forming an inductance which, taken together with the plates of said capacitor comprise the oscillatory circuit, means located externally of said surface for adjusting one of said support rods with respect to 45 the other, for varying the capacity between said plates, and leads coupled to said rods and extending substantially perpendicular thereto and through 50 said surface of revolution.
6. An ultra high frequency tuned oscillatory circuit comprising a container in the form of a metallic surface of revolution, a lumped capacitor substantially in the center of said surface of revolution and connected to said surface by inductance in the form of support rods, and leads 55 extending from said support rods externally of said surface of revolution, said leads being adjustable over the lengths of said rods.
7. A high frequency tuned oscillatory circuit comprising a substantially continuous metallic surface enclosing an inductance in the form of two metallic rods and a capacitor in the form of a pair of separated metallic plates, one end of each rod electrically terminating at one of the plates and the other end at the enclosing surface, and means for adjusting the length of one of the rods within said surface for varying the distance between said plates, and a lead connected to the outer surface of each of said support rods and extending externally of and through said surface. 60
8. An ultra-high frequency tuned oscillatory circuit comprising a container in the form of a substantially continuous metallic surface, a lumped capacitor substantially in the center of said surface and connected to said surface by inductances in the form of support rods, and a lead within said container connected to the outer surface of each of said support rods between the ends thereof and extending therefrom externally of and through said container, said leads being physically separated from each other. 65
9. A high frequency tuned oscillatory circuit comprising a container in the form of a substantially continuous metallic surface, a lumped capacitor within said surface, and a pair of inductance elements in the form of linear conductors devoid of concentrated reactance directly connecting said capacitor to said surface, and a lead within said container connected to the outer surface of each of said support rods between the ends thereof and extending externally of and through said container. 70
10. A high frequency tuned oscillatory circuit comprising a container in the form of a substantially continuous metallic surface, a lumped capacitor within said surface, a pair of inductance elements in the form of linear conductors devoid of concentrated reactance directly connecting said capacitor to said surface, and a lead conductively coupled to the outer surface of each of said inductance elements extending from within said container externally of said oscillatory circuit, and substantially at a right angle to its associated inductance elements. 75
11. A high frequency tuned oscillatory circuit comprising a container in the form of a substantially continuous metallic surface, a lumped capacitor within said surface and connected to said surface by inductance in the form of two support rods arranged substantially in the same straight line, and leads conductively coupled to the outer surface of said support rods and extending externally of said surface at substantially a right angle to said support rods. 80
12. A high frequency tuned oscillatory circuit comprising a substantially continuous metallic surface enclosing an inductance in the form of two metallic rods, and a capacitor in the form of a pair of separated metallic plates, one end of each rod electrically terminating at one of the plates and the other end at the enclosing surface, means for adjusting the length of one of said rods within said surface for varying the distance between said plates, and leads adjustable over the lengths of said rods and extending therefrom externally of said metallic surface. 85
